UNITED STATES PATENT OFFICE.

GEORGE WILLIAM BERRY, OF WAKEFIELD, ENGLAND, ASSIGNOR OF ONE-HALF TO
CHARLES JOSEPH RHODES, OF WAKEFIELD, ENGLAND.

DRAW PRESS FOR SHEET METAL.

Application filed February 21, 1924. Serial No. 694,221.

To all whom it may concern:

Be it known that I, GEORGE WILLIAM BERRY, a British subject, residing at Wakefield, in the county of York, England, have 5 invented certain new and useful Improvements in Draw Presses for Sheet Metal, of which the following is a specification.

This invention relates to draw presses for sheet metal and particularly to those which 10 are known as "combination" presses, that is to say, in which the lower die is provided with a movable pressure ring usually connected by pins passing through the bed of the press and operatively connected to a 15 resilient buffer composed for example of rubber and which receives the pressure exerted by the upper die during the drawing operation.

It has been proposed in presses of the 20 type mentioned to provide means whereby a predetermined pressure is constantly maintained on the pressure ring and also on the buffer at all stages of the drawing operation irrespective of the length or depth of draw 25 the latter function being in order that the resilient properties of the buffer may not be impaired.

The present invention comprises improved 30 means for the purpose or dual purposes above stated and these means embody a cam oscillated from a rotating part of the press and operatively connected to the pressure ring. This connection may be effected directly or through the medium of a resilient 35 buffer associated with the pressure ring, the oscillation of the cam being suitably effected by means of rack and pinion mechanism actuated from the main driving shaft of the press.

40 The invention also embodies the use of two pressure rings, with if required associated resilient buffers one for each of same, and operated by separate cams, such arrangement being for extra deep draws, one part 45 of the draw being performed between the inner and outer pressure rings and the other part between the outer pressure ring and the die.

The invention also comprises details of 50 construction arrangement and combinations of parts all as pointed out in appended claims and hereinafter fully described.

In the accompanying drawings.

55 Fig. 1 is a sectional front elevation of a press having the present improvements ap-

plied thereto, upper parts of the press being broken away. Fig. 2 is a side elevation from the left hand of Fig. 1 and Fig. 3 is a side elevation, partly in section, showing an embodiment of the invention and a modified arrangement of the die mechanism and its actuating means, which may be the preferred form of the invention, to effect a drawing of a blank in successive stages in a single movement of the reciprocating die. 60

In Figs. 1 and 2 *a* designates the press bed and *b* the side frames thereof between which are mounted the reciprocating ram or carrier for the upper die *c* with its usual or conventional spring plunger *c*¹ and the lower die *d* having the pressure element or ring *d*¹ connected by pins *d*² to a platform *d*³ which bears upon the buffer *e*. Now in this embodiment there is provided a rack and pinion mechanism *f* *f*¹ respectively operated by means of a crank disc *f*² or equivalent mounted on the main driving or crank shaft *g* of the press and coupled to the rack *f* as by means of a connecting rod *g*¹. The said rack is slideable in guides *f*³ on one side 70 of the press bed *s* and gears with the idle pinion *f*¹ which in turn meshes with another pinion *i* which is mounted on a cross shaft *i*¹ in the bed of the press and which also carries a cam *j* so that as the crank disc *f*² 75 is rotated the cam is caused to oscillate by means of the rack and pinion mechanism *f* *f*¹ said cam in turn acting on a bell crank *j*¹ which controls a supporting member *j*² for the buffer *e*. This supporting member 80 is guided on a stem *k* attached as by screwing at *k*¹ to the base of the lower die *d* and is carried by means of a yoke to *l* or similar element pivoted in links *l*¹ or the like 85 in such a manner that the support *j*² may move in a vertical path. The said support is screw threaded for reception of a nut *l*² which bears on the yoke *l* by adjustment of which nut the pressure of the buffer may be predetermined and varied as desired. Other 90 convenient means for the same purpose may however be adopted.

The rack and pinion mechanism *f* *f*¹ is so adjusted that when the upper die *c* engages the drawing pressure ring *d*¹ associated with the lower die *d* in a drawing operation the fall in the cam is in contact with a roller *j*¹⁰ or other antifriction device on the bell crank *j*¹ before mentioned, whereby the buffer is allowed to descend with the ring 100 110

*d*¹ at the same speed as said upper die *c* due to the contour of the cam and cause a perfectly uniform pressure to be maintained on the pressure ring *d*¹ and also on the buffer *e* throughout the length of the draw.

In the embodiment illustrated in Fig. 3 the press bed and frame, rack and pinion mechanism and crank disc with connections are not shown but are the same as described 10 with reference to Figs. 1 and 2.

This embodiment is particularly for use when it is desired to make extra long "draws" and means are provided whereby the drawing operation may be performed in two 15 stages in one drawing movement of the reciprocating upper die, for which purpose two buffers *m* *m*¹ and corresponding pressure rings *n* *n*¹ are provided with their respective controlling cams *x* *x*¹ mounted on cross 20 shaft *i*¹. The pressure rings *n* *n*¹ are arranged concentrically one within the other and of the stationary die and each acts through pins *o* *o*¹ respectively on a plate or frame *p* *p*¹ against which the respective buffers bear, the buffer supports *q* *q*¹ working one within the other and the support for the inner buffer passing through the outer buffer and the plate or frame *p*¹ of the outer pressure ring *n*¹. The outer support *q*¹ is operated 25 by links *q*² (one shown) and yoke *q*³ through a bell crank *q*⁴ acted on by cam *x*¹ and the inner support *q* is operated by links *r* (one shown) and yoke *r*¹ through double 30 armed lever *r*² acted on by cam *x*.

With such arrangement one part of the 35 draw is performed between the inner pressure ring *n* and the outer pressure ring *n*¹ the said inner ring being preferably curved or inclined at its upper edge *n*¹⁰ to avoid too sharp angles in the metal under treatment, and another part of the draw is performed 40 between the inner pressure ring *n* and the inner face of the die *s*. Other arrangements may however be made so long as the pressure rings are acted on successively by the upper die and transmit their movements in 45 similar sequence to the respective buffers each of which is controlled by an individual cam which ensures uniform pressure being maintained throughout the "draw". The cams 50 may be mounted coaxially as shown in Fig. 3 and be relatively adjustable as by means of slot and bolt connections *t* *t*¹ to determine and vary the point at which the first 55 draw terminates and the second draw commences.

In the arrangement of Figure 3 the reciprocating die *c* has a bore of two diameters 3 and 4 with a plunger *c*¹ slidably engaging 60 in the portion of least diameter and carried by a rod 6 which is slidably mounted axially of the die and normally urged outwardly to a predetermined position by a spring 7 coiled about the rod within the die, the outward 65 movement of the plunger being limited by

a nut 8 on the plunger rod abutting at the outer side of the die. In the operation of drawing the upper die *c* is reciprocated toward and away from the fixed die *d* by the press ram by a cam or crank on the shaft *g*. 70

As the upper die is moved toward the fixed die the effect produced is that after blanking, the metal to be drawn is gripped between the bottom face of the upper die portion of larger diameter and the top face of the pressure element or ring *n*', drawing the blank over the central fixed plug of the lower die and the pressure element *n* until the shoulder formed by the portion of the bore of reduced diameter comes into engagement 80 with the inner drawing element or ring *n* when the blank is drawn into the form of a shallow cup which engages in the portion of the upper die of larger diameter 3. During the continued descending movement of the upper die the partially drawn blank is gripped between the shoulder formed by the bore of the die of reduced diameter and the upper face of the drawing element or ring *n* when the blank is drawn to a reduced 85 diameter and extended length over the central plug of the fixed die. As the upper die is moved upward the rings *n*, *n*' participate in said movement through the action of the cams *x*, *x*¹ ejecting the drawn shell 90 from the fixed die and as the shell has a tendency to expand it causes it to be retained in the upper die, but as the upper die is cleared of the lower die the plunger *c*' through the influence of the spring 7 will 95 eject the drawn shell therefrom, or if desired means may be provided, such as a pivoted lever (not shown), to act upon the end of the plunger carrying rod 6 to eject the drawn shell from the upper die. 100

What I claim as my invention and desire to secure by Letters Patent of the United States is:—

1. In a draw press for sheet metal, co-operating movable and stationary dies, a pressure ring embodied in and movable relative to one of said dies, rack and pinion mechanism operative from a moving part of the press, a cam having a fixed axis actuated from said rack and pinion mechanism, and operative connections between said cam and pressure ring operative through the movement of the cam to control the movement of said pressure ring and maintain the same under a uniform pressure during the drawing operation. 115

2. In a draw press for sheet metal, co-operating reciprocating and stationary dies, a pressure ring embodied in and movable relative to one of said dies, a reciprocating support including a resilient buffer for said pressure ring, rack and pinion mechanism operated from a moving part of the press, an oscillatory cam operative through the movement of said rack and pinion, and op- 120 125 130

- erative connections between said cam and pressure ring support whereby said cam is operative to control the movement of the support for the pressure ring and maintain the buffer under uniform pressure during the entire drawing operation.
3. In a draw press for sheet metal, co-operating reciprocatory and stationary dies, a plurality of concentric elements embodied in one of said dies adapted to be moved relative to the central portion said die and each other through the movement of the reciprocatory die, a shaft, a cam for each of said elements on said shaft adapted to be actuated from a moving part of the press in unison with the movement of the reciprocatory die, and operative connections between said cams and elements to control the movement of said elements in predetermined successive sequence relative to the movement of the reciprocatory die during the drawing operation whereby said elements successively act as die and drawing elements.
4. In a draw press for sheet metal, co-operating reciprocatory and stationary dies, a plurality of rings embodied in one of said dies and disposed one within the other, a reciprocatory support including a resilient buffer for each of said rings, said rings being adapted to be moved by and participate in the movement of the reciprocatory die, a cam for each of said ring supports pivotally supported to have movement on an axis transverse to the direction of movement of the die mechanism and adapted to be oscillated in unison from a moving part of the press, and operative connections between said cams and ring supports to control the movement of the respective rings in predetermined successive sequence and maintain the same under uniform pressure during the entire drawing operation.
5. In a draw press for sheet metal, co-operating reciprocatory and stationary dies, a plurality of pressure rings embodied in one of said dies and disposed one within the other to have movement relative to said die and each other through the movement of the reciprocatory die, rack and pinion mechanism operated from a moving part of the press, a cam for each pressure ring adapted to be oscillated in unison with the movement of the reciprocatory die through the actuation of said rack and pinion mechanism, and operative connections between said cams and pressure rings to control the movement of the latter by the movement of the reciprocatory die in predetermined successive sequence and maintain the same under uniform pressure during the entire drawing operation.
6. In a draw press for sheet metal, co-operating reciprocatory and stationary dies, a pressure ring embodied in one of said dies, a pivotally supported cam adapted to be oscillated from a rotating part of the press, operative connections between said cam and pressure ring to maintain said ring under predetermined uniform pressure during the entire drawing operation, and means for adjusting said connections to vary the pressure on said pressure ring.
7. In a draw press for sheet metal, co-operating reciprocatory and stationary dies, a pressure ring embodied in one of said dies, a slidably mounted support including a resilient buffer for said pressure ring, a pivotally mounted cam, means to connect said cam with a rotating part of the press operative to oscillate said cam in unison with the movement of the reciprocatory die, operative connections between said cam and ring support to control the movement of the ring and maintain the same under a uniform pressure during the drawing operation, and means for adjusting said operative connections to determine and vary the pressure on said buffer and pressure ring.
8. In a draw press for sheet metal, co-operating reciprocatory and stationary dies, a plurality of pressure rings embodied in one of said dies, and disposed one within the other to have independent movement relative to said die and each other, a cam for each of said pressure rings, means to connect and oscillate said cams from a moving part of the press, connections between said cams and pressure rings operative to maintain the rings under a uniform pressure by the movement of the cams during the entire drawing operation, and means for adjusting said cams to vary the relative period of operation of said pressure rings.
9. In a draw press for sheet metal, co-operating, reciprocatory and stationary dies, a plurality of pressure rings embodied in one of said dies and disposed one within the other to have independent movement relative to said die and each other, rack and pinion mechanism operated by a moving part of the press, cams for said pressure rings adapted to be oscillated through the actuation of said rack and pinion mechanism, connections between said cams and pressure rings operative to control the movement of said rings in succession and maintain the same under uniform pressure during the entire drawing operation, and means for adjusting said cams to control the relative period of commencement of movement of said pressure rings.
10. In a press for drawing sheet metal hollow ware, the combination of a stationary die, a movable drawing member embodied in said die, a cam, connections between said cam and drawing member, rack and pinion mechanism in operative connection with said cam, and a positive connection between said rack and a moving part of the press whereby the cam is oscillated and uniform

pressure maintained on the drawing member during the entire drawing operation.

11. In a draw press for sheet metal, the combination of a die, a plurality of members embodied in and movable relative to said die and each other, a cam for each of said members movable on an axis transverse to the direction of movement of said members and operatively connected thereto, and means positively operated by a moving part of the press for oscillating said cams whereby the said members are adapted to have movement in succession to effect a drawing operation in successive stages and uniform pressure is maintained on the work during the entire drawing operation.

12. In a draw press for sheet metal, the combination of a stationary die, a plurality of drawing members embodied in said die and disposed one within the other, a plurality of cams, connections between the cams and said pressure members, rack and pinion mechanism in operative connection with said cams, and positive driving means from a moving part of the press whereby the cams are oscillated and the drawing members are movable in succession to effect a drawing operation in successive stages while uniform pressure is maintained on the work during the entire drawing operation.

13. In a draw press for sheet metal, the combination of a die, a plurality of members arranged concentrically of and movable relative to said die and each other, a cam for each of said members movable on an axis transverse to the direction of movement of and operatively connected to said members, and means positively operated by a moving part of the press for oscillating said cams to control the movement of said members to effect a drawing operation in successive stages during a single stroke of the press.

14. In a draw press for sheet metal, the combination of a die, a plurality of members embodied in and movable relative to said die and each other, a cam for each member, operative connections between each cam and the respective members, means positively operated by a moving part of the press for oscillating said cams whereby the drawing members are movable in predetermined sequence to effect a drawing operation in successive stages in a single stroke of the press, and means for adjusting the aforesaid operative connections to vary the pressure on said drawing members.

15. In drawing sheet metal, a fixed die and a plurality of elements arranged concentrically of and independently movable relative to the die and each other, a die reciprocatory toward and away from said fixed die, means to reciprocate said die, and means operative by the die reciprocating means to control the movement of and place

the movable elements under a constraining force having a constant value, and said reciprocatory die successively co-operating with said movable elements and the fixed die to effect a drawing of the metal in successive stages in a single movement of the reciprocatory die.

16. In drawing sheet metal, a fixed die and a plurality of elements movable relative thereto, a die reciprocatory toward and away from said elements and the fixed die, means to reciprocate the reciprocatory die, pressure buffers to exert a yielding force upon said movable elements in a direction toward the reciprocatory die, and cams operative from the movement of the die reciprocating means to maintain said pressure buffer and movable elements under a force having a predetermined and constant value, and said reciprocatory die co-operating with said movable elements and the fixed die to effect a drawing of the metal in successive stages in a single movement of the reciprocatory die.

17. In a draw press for sheet metal, co-operating reciprocatory and stationary dies, and a plurality of elements arranged concentrically of one of said dies and movable relative to said die and each other through the movement of the reciprocatory die, and with which elements the other die is adapted to successively co-operate to effect a drawing operation in successive stages by a single movement of the reciprocatory die, and means for controlling the movement of and maintain said element under a force of constant value to resist the movement thereof by the reciprocatory die.

18. In a press for drawing sheet metal, a die embodying a central fixed plug and a plurality of elements arranged concentric of each other and said plug and movable relative to said plug and each other, reciprocatory supports for said elements, and cams oscillatory on an axis transverse to the direction of movement of said element and operated from a moving part of the press engaging said supports and controlling the movement of the elements relative to the plug and each other.

19. In drawing sheet metal, a fixed die and a plurality of concentrically arranged and independently movable die and drawing elements movable relative thereto and each other, a die reciprocatory toward and away from the fixed die adapted to impart participating movement to the die and drawing elements, a shaft extending transverse of the die mechanism, cams on said shaft; and means operative to oscillate said shaft and cams in unison with the movement of the reciprocatory die and co-operate with said die and drawing elements to place said elements under a constant force to resist the movement thereof by the reciprocatory die,

- and the reciprocatory die co-operating with the die and drawing elements and the fixed die to effect a drawing in successive stages in a single movement of the reciprocatory die.
20. In drawing sheet metal, co-operating reciprocatory and fixed dies, a plurality of concentrically arranged and combined die and drawing members associated with and movable independently relative to one of said dies and each other and adapted to have movement imparted thereto through the movement of the reciprocatory die, a cam for each of said die and drawing members pivotally supported to have movement on an axis transverse to the movement of the die mechanism, and means operative from the movement of the reciprocatory die to move said cams to control the movement of said concentrically arranged die and drawing members in predetermined successive sequence relative to the movement of the reciprocatory die and exert a force on said members in a direction toward and to resist the movement thereof by the reciprocatory die.
21. In drawing sheet metal, co-operating reciprocatory and fixed dies, a plurality of concentrically arranged and combined die and drawing members associated with and independently movable relative to one of said dies and each other and adapted to have movement imparted thereto by and participate in the movement of the reciprocatory die, and cams pivotally supported to have movement on an axis transversely to the movement of the die mechanism and co-operating with the die and drawing members to control the movement thereof in predetermined successive sequence relative to the movement of the reciprocatory die and exert a pressure with a predetermined force on said members in a direction toward and resist the movement thereof by the reciprocatory die.
22. In drawing sheet metal, a die including a fixed element and a plurality of concentrically arranged elements independently movable relative to the fixed element and each other, a die reciprocatory toward and away from the first die and adapted to impart movement to the movable elements of said first die, and cams pivotally supported to have movement on an axis transverse to the direction of movement of the die mechanism and adapted to co-operate with the movable elements to control the movement thereof by the reciprocatory die in successive sequence and resist the movement thereof by the reciprocatory die to effect the drawing of a blank in successive stages in a single movement of the reciprocatory die.
23. In drawing sheet metal, a fixed blank-
- ing die, a second die arranged in concentric and spaced relation to the blanking die including a fixed element and a plurality of elements movable relative to the fixed element and each other, a die reciprocatory toward and away from said dies and arranged to co-operate with the blanking die to cut a blank and with the movable elements of one die to impart movement thereto in successive sequence, and cams pivotally supported to have movement on an axis transverse to the direction of movement of the die mechanism to co-operate with the movable die elements to control and resist the movement thereof by the reciprocatory die to effect a cutting and drawing of the cutting blank in successive stages in a single movement of the reciprocatory die.
24. In drawing sheet metal, a pair of dies one of which is fixed and the other reciprocatory relative to the fixed die, one of said dies comprising a one piece block arranged with a bore having successive portions of reduced cross sectional area and the other die provided with auxiliary combined die and drawing members arranged about and movable independently relative to the die and each other to engage in the bore of the one die and adapted to be successively moved through the movement of the reciprocatory die by the engagement thereof with the shoulders formed by the reduced portions of the die bore to effect a drawing in successive stages in a single movement of the reciprocatory die, and means to control the movement of and exert a pressure of a constant force on said auxiliary die and drawing members to resist the movement thereof through the movement of the reciprocatory die during the entire drawing operation.
25. In drawing sheet metal, a reciprocatory die comprising a one piece block arranged with a bore having successive portions of reduced cross sectional area, a fixed die, a plurality of combined die and drawing members arranged about and movable independently relative to the fixed die and each other and adapted to be moved through the movement of the reciprocatory die by the engagement thereof with the shoulders formed in the bore of the reciprocatory die by the portions of reduced area, and means operative from the movement of the reciprocatory die to control the movement of said die and drawing members and exert a pressure thereon having a constant force to resist the movement thereof by the reciprocatory die for the entire drawing operation.

In witness whereof I have signed this specification.

GEORGE WILLIAM BERRY.
